UNITED STATES PATENT OFFICE.

HARRY J. DURBOROW, OF PHILADELPHIA, PENNSYLVANIA.

SOUND BOX.

1,426,970.

Specification of Letters Patent. Patented Aug. 22, 1922.

Application filed December 16, 1920. Serial No. 431,069.

To all whom it may concern:

Be it known that I, HARRY J. DURBOROW, a citizen of the United States, residing at Philadelphia, in the county of Philadelphia and State of Pennsylvania, have invented 5 certain new and useful Improvements in Sound Boxes, of which the following is a specification.

One object of my invention is to provide 10 an improved sound box for talking machines, which will be instrumental in more accurately reproducing sound than devices previously used for this purpose.

Another object of my present invention is 15 to distribute and equalize the impulse caused by the connection of the stylus bar to the diaphragm prior to the passage of the sound waves through the tone conducting portion of the machine.

20 A further object is to make the device of my invention of a simple and durable construction which can be readily manufactured.

25 These objects, and other advantageous ends which will be described hereinafter, I attain in the following manner, reference being had to the accompanying drawings in which

30 Figure 1 is an enlarged fragmentary section taken centrally through a sound box made in accordance with my invention; the stylus bar being shown in outside view;

Figure 2 is a section taken on the line 2—2 of Figure 1,

35 Figure 3 is a front face view of a member which forms a part of my invention in the construction illustrated,

Figure 4 is an edge view of said member, and

40 Figure 5 is a rear view of said member.

Referring to the drawings, 6 represents the frame of a sound box including a recess 7 in which is mounted a diaphragm 8; said diaphragm being positioned between

45 gaskets 9 and 10; the gaskets being confined within the recess and between a ring 11 and a shoulder 12. A circular cavity 13 leads inwardly from the shoulder 12 and communicates with an axial passage 14

50 which forms a part of the sound conducting passage and is provided by a nipple extension or sleeve 15 whereby the sound box can be attached to a tone arm or other sound conducting member as is common practice in the manufacture of talking ma-

chines. The stylus bar 16 is centrally connected at 17 to the diaphragm 8.

A member 18, the detail construction of which is shown in Figures 3 to 5 inclusive, fits within the cavity 13 and is held between the inner surface or wall 19 of said cavity 13 and the gasket 10. This member 13 may be made of hard or tough springy wood and on its rear face has a number of radially extending grooves 21. These 65 grooves communicate with each other at the axis of the member 18 and lead outwardly to respective notches 22 which are cut into the peripheral edge portion; said notches communicating with the space between the diaphragm 8 and the front face 23 of the member 18. The portions of the face 20 between the grooves 21 preferably engage the wall 19 and the gaskets 9 and 10 are preferably made of rubber so as to 70 resiliently hold the member 18 in place. Thus there is a solid portion of the member 18 interposed between the central connection of the stylus bar with the diaphragm and the sound outlet 14; the diaphragm 8 75 also being spaced from the face surface 23 of the member 18 to provide a chamber 24. The vibrations of the stylus bar 16 affect the diaphragm 8, the greatest impulse occurring adjacent the axis or central portion of the diaphragm, and sound waves are set up in the chamber 24; the stronger waves occurring in the central portion of said space. Ordinarily these 80 stronger sound waves would precede other 85 portions of the waves directly outward through the passage 14 if the member 18 were not present. With my improved structure, however, all of the sound waves are compelled to pass radially or to spread 90 out from the axis of the chamber 24 and eventually pass through the notches 22 and grooves 21 and finally pass through the passage.

I have found in actual experience that a 100 more clear and definite reproduction is produced by the construction above described and also that the member 18 serves as a resonator which greatly improves the quality 105 of the sound.

The member 18 therefore forms a resonating partition which also serves in the capacity as a distributor and equalizer for the sound waves set up by the vibration of the diaphragm.

While I have described my invention as taking a particular form, it will be understood that the various parts of my invention may be changed without departing 5 from the spirit thereof, and hence I do not limit myself to the precise construction set forth, but consider that I am at liberty to make such changes and alterations as fairly come within the scope of the appended 10 claims.

Having thus described my invention, what I claim as new and desire to secure by Letters Patent is:—

- 15 1. A resonating partition for use in a talking machine sound box case including a portion providing a sound outlet passage, said partition being located between the diaphragm and the sound outlet passage of the case, said partition having grooves in one face and sound outlet openings communicating with said grooves, said grooves also being in communication with said sound outlet passage of the case; substantially as described.
- 20 2. A resonating partition for use in a talking machine sound box case including an inner wall having a sound outlet passage, said partition being located between the

diaphragm and the inner wall of the case, 30 said partition having passages leading toward the axis thereof and being in communication with the sound outlet passage and with the space between the partition and the diaphragm; substantially as described.

3. A resonating partition for use in a talking machine sound box case including an inner wall having a sound outlet passage, 40 said partition being located between the diaphragm and the inner wall of the case, 45 said partition having grooves in one face and notches communicating with said grooves, said partition being adapted to be placed in said case with said face opposed to said wall of the case so that said grooves provide passages communicating with the outlet passage and with said notches; substantially as described.

In testimony whereof I have signed my name to this specification in the presence 50 of two subscribing witnesses.

HARRY J. DURBOROW.
